United States Patent Office

Des. 193,215
Patented July 10, 1962

193,215

FOOD TRANSPORTING BASKET

William H. Fredrick, Los Angeles, Calif., assignor of
one-half to Nathan Gilbert, Burbank, Calif.

Filed Dec. 12, 1961, Ser. No. 67,887

Term of patent 14 years

(Cl. D58—4)

FIG. 1.

FIG. 2.

FIG. 3.

FIG. 4.

FIG. 1 is a side elevational view of a food transporting basket showing my new design;

FIG. 2 is a top plan view thereof;

FIG. 3 is a bottom plan view thereof;

FIG. 4 is an end elevational view thereof.

I claim:

The ornamental design for a food transporting basket, as shown.
